UNITED STATES PATENT OFFICE.

WILLIAM H. PAGE, OF PRESTON, CONNECTICUT.

DESIGN FOR A FONT OF PRINTING-TYPES.

SPECIFICATION forming part of Design No. 12,021, dated November 9, 1880.

Application filed June 16, 1880. Term of patent 7 years.

To all whom it may concern:

Be it known that I, WILLIAM H. PAGE, a citizen of the United States, residing at Preston, in the county of New London and State of Connecticut, have invented and produced a new and original Design for a Font of Printing-Types, of which the following is a specification.

The nature of my invention is clearly illustrated in the accompanying typographic im-

pression, to which, for a clear understanding thereof, reference is made; and it consists in the letters, as fully shown.

What I claim as new is—

The design for a font of printing-types, as 15 herein shown and described.

WILLIAM H. PAGE.
